UNITED STATES PATENT OFFICE.

DUDLEY D. WRIGHT, OF SAN FRANCISCO, CALIFORNIA.

TELEPHONE SIGNALING APPARATUS.

1,108,305.

Specification of Letters Patent. Patented Aug. 25, 1914.

Application filed November 27, 1912. Serial No. 733,825.

To all whom it may concern:

Be it known that I, DUDLEY D. WRIGHT, a citizen of the United States, residing at San Francisco, in the county of San Francisco and State of California, have invented a new and useful Telephone Signaling Apparatus, of which the following is a specification.

The object of my invention is to produce an apparatus which may be installed in conjunction with a subscriber's telephone, and which, upon proper setting, and upon the sending in of a call to the associated telephone, will operate automatically to advise the calling subscriber or the central operator in accordance with a predetermined code signal. There may be any desired number of signals in the code, and a subscriber, as when leaving his home or office, may set the device to give any desired or suitable one of these signals.

The accompanying drawings illustrate my invention.

Figure 1 is an axial section through my apparatus, substantially on the line 1—1 of Fig. 5; Fig. 2 is a section on the line 2—2 of Fig. 1; Fig. 3 is a partial view similar to part of Fig. 2, but showing the roller 23 in a different position; Fig. 4 is a front elevation of the device shown in Fig. 1; Fig. 5 is a section on the line 5—5 of Fig. 1, and also shows the electrical connections diagrammatically; Fig. 6 is a perspective view showing one of the adjustable segments; and Figs. 7, 8, and 9 are diagrammatic views showing the setting of the switches for different types of telephone systems and the setting of the segments for different signals.

A suitable motor 10, conveniently a spring motor provided with a governor 11 and a winding stem 12, tends to drive a shaft 13, on one end of which is mounted an arm 14 carrying an inwardly projecting contact finger 15 which, when the shaft 13 rotates, sweeps around a commutator 16 in a groove 17 in the circumference thereof. The shaft 13 carries a stop disk 20 having an annular flange 21 and carrying stop rollers 22 and 23 on the outside and inside of such flange. The roller 23 is slightly angularly spaced from the roller 22, and may be placed either angularly behind (as indicated in Fig. 2) or angularly ahead (as indicated in Fig. 3) of the roller 22 to suit different telephone systems as hereinafter explained. A slotted dog 24, the slot in which is wide enough

to allow the passage of the flange 21 and one or the other but not both of the rollers 22 and 23, is slidably mounted in a standard 25, conveniently being provided with a guide fork 24 straddling the shaft 13; and is connected, by a pin and slot connection 26, to the core 27 of a solenoid 28. The pin and slot connection 26 allows the core 27 to operate the dog 24 by a hammer blow, so that sticking is effectually prevented.

The commutator 16 has a body of insulation material, and is suitably supported, as on a standard 30. A shaft 31, in alinement with the shaft 13 but insulated therefrom, extends axially through the commutator 16, conveniently being supported in the standard 30; and surrounding such shaft 31, but not extending through the commutator 16, is a sleeve 32. On the inner ends of the shaft 31 and sleeve 32 are mounted contact segments 33 and 34 respectively, of the shape shown in perspective in Fig. 6. These contact segments are conveniently slotted to form individual contact fingers 33' and 34' at their periphery, which fingers bear against the exposed ends of two circular series of pins 35 and 36 upon proper movement of the segments 33 and 34 by setting handles 37 and 38 on the outer or front ends of the shaft 31 and the sleeve 32. A suitable dial may be mounted on the front of the standard 30 to give indication of the number of pins 35 or 36 with which the segments 33 and 34 are respectively in engagement, and if desired one or more of the fingers 33' or 34' may be provided with a notch or recess 40 (Fig. 6) to enable the operator to "feel" when the segments 33 or 34 are in a proper position.

The pins 35 and 36 project into the body of the commutator 16 from opposite sides, and are exposed in the bottom of the groove 17 so that they will be engaged by the contact 15 as the latter sweeps around the commutator. A plate 41 is embedded in the bottom of the slot 17 in position to be engaged by the contact finger 15 when the latter is in normal position, and a pin 42 is embedded in the same face of the commutator 16 as are the pins 35, but is engaged by the segment 33 only when the latter is not in engagement with any of the pins 35. Suitable binding posts 43, 44, 45, 46, and 47 are respectively connected to the shaft 13 or its supporting standards, the shaft 31 and sleeve 32 or their supporting standard

30, that one of the pins 35 which is nearest the plate 41, and the pin 42.

A triple pole switch 51 and a double pole switch 52 are provided for connecting the apparatus for different types of telephone systems. When a number of the devices are to be used for a number of similar telephones, the switches 51 and 52 may be omitted and the permanent connections 10 made to suit the installation. The three arms 53, 54, and 55 of the switch 51 co-operate with four contact buttons 56, 57, 58, and 59, said arms engaging the buttons 56, 57, and 59 respectively when the switch is raised and the arms 53 and 54 engaging the buttons 57 and 58 respectively when the switch is lowered. The two arms 60 and 61 of the switch 52 co-operate with four contact buttons 62, 63, 64, and 65, the two arms 20 engaging the buttons 62 and 64 respectively when the switch is raised and the buttons 63 and 65 respectively when the switch is lowered.

The contact 15 is connected through the 25 arm 14, the shaft 13, the spring motor standard, and the binding post 43 to the switch arm 54; the segments 33 and 34 are connected through the shaft 31 and sleeve 32, the standard 30, and the binding post 44 to the switch button 63, and also to one side A of the telephone transmission line; the first pin 35 is connected through the binding post 45 to the switch arm 53; the contact plate 41 is connected through the binding post 46 to the switch button 56; the pin 42 is connected through the binding post 47 to the switch button 62; the solenoid 28 is connected between the switch buttons 57 and 59; a condenser 66 is connected between the 30 switch arm 55 and the switch button 59; an inductance 67 has one terminal connected to the switch button 58 and the other to both switch arms 55 and 61; the switch arm 60 and the switch button 64 are connected 45 together and to one side of the polarized bell or telephone ringer 68, the other side of which is suitably connected to the telephone apparatus; the telephone apparatus is suitably connected between the two wires A and 50 B of the telephone transmission system; and the wire B is connected to the switch button 65.

By different settings of the two switches 55 51 and 52, the device may be connected in several different ways, to suit the different systems of telephone connections in general use. By setting both switches 51 and 52 down, the set of connections shown in Fig. 7, suitable for common battery systems 60 where alternating current is used for ringing purposes, but where direct current is used for telephoning and other signal purposes, is obtained. By setting both switches 51 and 52 up, the set of connections shown 65 in Fig. 8, suitable for local battery systems

where alternating current is used for all signaling and that by which the subscriber calls up is produced by a hand operated magneto, is obtained. By setting switch 51 up and switch 52 down, the set of connections shown in Fig. 9, suitable for the same system as that shown in Fig. 8 is obtained. The difference between the systems in Figs. 8 and 9 is that in Fig. 8 my signaling device is connected in series with the polarized bell 68 while in Fig. 9 it is connected in shunt thereto. 70 75

In the system shown in Fig. 7, the roller 23 is angularly behind the roller 22, as shown in Fig. 2, and the roller 22 normally bears against the dog 24. The subscriber is called by alternating current coming in over the wire A, passing through the switch button 63 and switch arm 60 to the polarized bell 68, and thence through the usual condenser 70 to the other side B of the transmission line. Assume that prior to this call the subscriber has set his automatic signaling device to give a desired code signal, say 2-1; which is done by turning the 90 handle 37 counter clockwise (as seen in Fig. 4) to move the segment 33 counter clockwise (as seen in Fig. 5) to engage the first two of the pins 35, and the handle 38 clockwise (as seen in Fig. 4) to move the segment 34 clockwise (as seen in Fig. 5) to engage the first one of the pins 36. The ringing current from the central office then, in addition to ringing the bell 68 as above described, also passes, in shunt to the circuit above traced, from the wire A through the shaft 31, segment 33, the first pin 35, switch arm 53, switch button 57, solenoid 28, condenser 66, switch arm 61, and switch button 65 to the wire B. The resultant energization of the solenoid 28 lifts the core 27 and dog 24 to permit the roller 22 to pass through the slot in such dog; as a result, the spring motor 10 drives the shaft 13 slightly forward, or counter clockwise (as seen in Fig. 2), until the roller 23 strikes the dog 24. When the ringing current ceases, the solenoid 28 is deenergized and the dog 24 drops, thereby allowing the roller 23 to pass through the slot in the dog and the 100 spring motor 10 to drive the shaft 13 and arm 14 forward until the roller 22 again strikes the dog. In this movement the contact finger 15 successively engages the several contact pins 35 and then the several 105 contact pins 36. As it engages any of such pins which is also engaged by the segment 33 or 34, a circuit is completed from the wire A through the shaft 31, segment 33 or 34, pin 35 or 36, contact finger 15, arm 14, 110 switch arm 54, switch button 58, inductance 67, switch arm 61, and switch button 65 to the wire B, thereby allowing a direct current impulse to pass to give a suitable signal, as a flash of a signal lamp or a tap in 115 120 125 130

the telephone receiver, to the operator at central. With the segments 33 or 34 set as shown in Fig. 7, the central operator receives two flashes or taps as the finger 15 passes the first two pins 35, and then, after a space while the finger 15 moves over the unconnected pins 35 and 36, one flash or tap as such finger passes the pin 36 which is engaged by the segment 34. The condenser 66 prevents these direct current impulses from passing through the solenoid 28 to energize it, and the inductance 67 prevents the passage of the high frequency voice currents through the automatic signaling device. 15 When the automatic signaling device is made only for use with this system of connection, the contact plate 41 and the pin 42 may be omitted; as may also the switches 51 and 52 if the switch connections shown in Fig. 7 are made permanently.

In the systems shown in Figs. 8 and 9, the roller 23 is placed angularly ahead of the roller 22, as shown in Fig. 3, and the roller 22, as before, normally bears against the dog 24. In the system shown in Fig. 8, the ringing current from the central station, coming in through the wire A, passes to the shaft 31 and segment 33. If the device is not set for automatic signaling, the current then passes through the pin 42, switch button 62, and switch arm 60 to the polarized bell 68, and thence to the line B. If the device is set for automatic signaling, the ringing current passes from the segment 33 through the first pin 35, switch arm 53, switch button 56, plate 41, contact finger 15, arm 14, switch arm 54, switch button 57, solenoid 28, switch button 59, switch arm 55, switch arm 61, and switch button 64 to the polarized bell 68, and thence to the line B as before. This energizes the solenoid 28 so that the core 27 lifts the dog 24 to allow the passage of the roller 22, whereupon the spring motor 10 drives the arm 14 and contact finger 15 around the commutator 16 until the roller 23 engages the dog 24, breaking the ringing current as the contact finger 15 leaves the plate 41 and producing a make and break of the ringing current as each pin 35 and 36 engaged by the segment 33 and 34 is passed by the contact finger 15. This making and breaking of the circuit produces flashes of the signal light or taps in the telephone receiver of the central operator, the number of flashes or taps depending upon the setting of the segments 33 and 34, or indicating 3-2 with the setting of the segments shown in Fig. 8. The rotation of the shaft 13 stops when the roller 23 strikes the dog 24; and thereafter, when the incoming current is stopped, the solenoid 28 is deenergized and the dog 24 drops to allow the passage of the roller 23, and the stoppage of the roller 22 in normal position. When the automatic signaling device is made only for use with this system of

connection, the condenser 66 and the inductance 67 may be omitted; as may also the switches 51 and 52 if the switch connections shown in Fig. 8 are made permanently.

In the system shown in Fig. 9 the ringing current coming in over the line A passes through the switch button 63 and the switch 60 to the polarized bell 68, and thence to the line B. A shunt current also passes from the line A to the shaft 31, and thence, if the device is set for automatic signaling, through the segment 33, the first pin 35, switch arm 53, switch button 56, plate 41, contact finger 15, arm 14, switch arm 54, switch button 57, solenoid 28, switch button 59, switch arm 55, switch arm 61, and switch button 65 to the line B. This shunt current energizes the solenoid 28, and the resultant lifting of the dog 24 allows the spring motor 10 to drive the finger 15 around the commutator 16, and the changes in current flow upon the making and breaking of the shunt circuit produced by the engagement and disengagement of the finger 15 with which those pins 35 and 36 which are in contact with the segments 33 and 34 produce flashes or taps or other signals as before, giving the code signal 5-3 with the segments 33 and 34 set as shown in Fig. 9. When the automatic signaling device is made only for use with this system shown in Fig. 9, the condenser 66, the inductance 67, and the pin 42 may be omitted; as may also the switches 51 and 52 if the switch connections shown in Fig. 9 are made permanently.

I claim as my invention:

1. An automatic telephone signaling apparatus for producing a code signal, comprising a series of contacts, a contact finger movable over said contacts in cyclic succession, a spring motor for producing such movement, means for varying the effective arrangement of said contacts, and means controlled by an incoming calling current to the associated telephone for causing the movement of said contact finger over said contacts by said spring motor and for necessarily stopping said movement at the end of a complete cycle until another incoming calling current separate from the first shall be supplied subsequent to the completion of such cycle.

2. An automatic telephone signaling apparatus for producing a code signal, comprising a series of contacts, a contact finger movable over said contacts in cyclic succession, means for varying the effective arrangement of said contacts, and means controlled by an incoming calling current to the associated telephone for causing the movement of said contact finger over said contacts for a complete cycle and for necessarily stopping such movement at the end of such cycle until another incoming calling current separate from the first shall be sup-

plied subsequent to the completion of such cycle.

3. An automatic telephone signaling apparatus for producing a code signal, comprising a series of contacts, a contact finger movable over said contacts in cyclic succession, a spring motor for producing such movement, and means controlled by an incoming calling current to the associated telephone for causing the movement of said contact finger over said contacts by said spring motor and for necessarily stopping said movement at the end of a complete cycle until another incoming calling current separate from the first shall be supplied subsequent to the completion of such cycle.

4. An automatic telephone signaling apparatus for producing a code signal, comprising a series of contacts, a contact finger movable over said contacts in cyclic succession, and means controlled by an incoming calling current to the associated telephone for causing the movement of said contact finger and for necessarily stopping said movement at the end of a complete cycle until another incoming calling current separate from the first shall be supplied subsequent to the completion of such cycle.

5. An automatic telephone signaling apparatus for producing a code signal, comprising a device for automatically making and breaking a circuit in a plurality of time-separated groups of makes and breaks, means for setting such device to vary the number of makes and breaks produced in the several groups in an operation, and means controlled by an incoming calling current to the associated telephone for starting the operation of said circuit making and breaking means and for causing such operation necessarily to stop upon the completion of the last of the groups of makes and breaks until another incoming calling current separate from the first shall be supplied subsequent to such completion.

6. An automatic telephone signaling apparatus for producing a code signal, comprising a series of contacts, a contact finger arranged to sweep over said contacts, a spring motor for driving said contact finger over said contacts, said contacts and said contact fingers being connected so that the passage of the contact finger over the contacts produces a series of impulses in a circuit, means for changing the connection of said contacts to vary the signal produced, and means responsive to an incoming calling current to the associated telephone for causing said contact finger to be moved over said contacts by said motor and necessarily to stop after making a complete cycle of movement over said contacts until another incoming calling current separate from the first shall be supplied subsequent to the completion of such cycle.

7. An automatic telephone signaling apparatus for producing a code signal, comprising a series of contacts, a contact finger arranged to sweep over said contacts, said contacts and said contact finger being connected so that the passage of the contact finger over the contacts produces a series of impulses in a circuit, means for changing the connection of said contacts to vary the signal produced, and means responsive to an incoming calling current to the associated telephone for causing said contact finger to be moved over said contacts and necessarily to stop after making a complete cycle of movement over said contacts until another incoming calling current separate from the first shall be supplied subsequent to the completion of such cycle.

8. An automatic telephone signaling apparatus for producing a code signal, comprising a series of contacts, a contact finger arranged to sweep over said contacts, a spring motor for driving said contact finger over said contacts, said contacts and said contact finger being connected so that the passage of the contact finger over the contacts produces a series of impulses in a circuit, and means responsive to an incoming calling current to the associated telephone for causing said contact finger to be moved over said contacts by said motor and necessarily to stop after making a complete cycle of movement over said contacts until another incoming calling current separate from the first shall be supplied subsequent to the completion of such cycle.

9. An automatic telephone signaling apparatus for producing a code signal, comprising a series of contacts, a contact finger arranged to sweep over said contacts, said contacts and said contact finger being connected so that the passage of the contact finger over the contacts produces a series of impulses in a circuit, and means responsive to an incoming calling current to the associated telephone for causing said contact finger to be moved over said contacts and necessarily to stop after making a complete cycle of movement over said contacts until another incoming calling current separate from the first shall be supplied subsequent to the completion of such cycle.

10. An automatic telephone signaling apparatus for producing a code signal, comprising a series of contacts, a contact finger arranged to sweep over said contacts, a spring motor for driving said contact finger over said contacts, said contacts and said contact finger being connected so that the passage of the contact finger over the contacts produces a series of impulses in a circuit, means for changing the connections of said contacts to vary the signal produced, stopping means which in one position permits a partial movement of said contact

finger and prevents the remainder of said movement and in another position permits such remainder while preventing the first named partial movement, and electro-magnetic means responsive to an incoming calling current to the associated telephone for controlling said stopping means to permit the movement of said contact finger over said contacts by said spring motor.

11. An automatic telephone signaling apparatus for producing a code signal, comprising a series of contacts, a contact finger arranged to sweep over said contacts, said contacts and said contact finger being connected so that the passage of the contact finger over the contacts produces a series of impulses in a circuit, means for changing the connections of said contacts to vary the signal produced, stopping means which in one position permits a partial movement of said contact finger and prevents the remainder of said movement and in another position permits such remainder while preventing the first named partial movement, and electro-magnetic means responsive to an incoming calling current to the associated telephone for controlling said stopping means to permit the movement of said contact finger over said contacts.

12. An automatic telephone signaling apparatus for producing a code signal, comprising a series of contacts, a contact finger arranged to sweep over said contacts, said contacts and said contact finger being connected so that the passage of the contact finger over the contacts produces a series of impulses in a circuit, stopping means which in one position permits a partial movement of said contact finger and prevents the remainder of said movement and in another position permits such remainder while preventing the first named partial movement, and electro-magnetic means responsive to an incoming calling current to the associated telephone for controlling said stopping means to permit the movement of said contact finger over said contacts.

13. An automatic telephone signaling apparatus for producing a code signal, comprising a series of contacts, a contact finger arranged to sweep over said contacts, a spring motor for driving said contact finger over said contacts, said contacts and said contact finger being connected so that the passage of the contact finger over the contacts produces a series of impulses in a circuit, stopping means which in one position permits a partial movement of said contact finger and prevents the remainder of said movement and in another position permits such remainder while preventing the first named partial movement, and electro-magnetic means responsive to an incoming calling current to the associated telephone for controlling said stopping means to permit

the movement of said contact finger over said contacts by said spring motor.

14. An automatic telephone signaling apparatus for producing a code signal, comprising a rotatable contact finger, a series 70 of contacts over which said contact finger is movable, a rotatable segment movable to engage different combinations of said contacts, said contact finger and said segment being suitably connected so that when they 75 are connected together through one of said contacts a signaling impulse is produced, and means controlled by an incoming calling current to the associated telephone for causing said contact finger to move over said 80 contacts and necessarily to stop after having made one complete rotation until another incoming calling current separate from the first shall be supplied subsequent to the completion of such rotation.

15. An automatic telephone signaling apparatus for producing a code signal, comprising a rotatable contact finger, a series of contacts over which said contact finger is movable, a rotatable segment movable to 90 engage different combinations of said contacts, said contact finger and said segment being suitably connected so that when they are connected together through one of said contacts a signaling impulse is produced, a 95 spring motor for driving said contact finger over said contacts, and means controlled by an incoming calling current to the associated telephone for causing said motor to drive said contact finger over said contacts and 100 necessarily to stop after having made one complete rotation until another incoming calling current separate from the first shall be supplied subsequent to the completion of such rotation.

16. An automatic telephone signaling apparatus for producing a code signal, comprising a rotatable contact finger, a series of contacts over which said contact finger is movable, a rotatable segment movable to 110 engage different combinations of said contacts, said contact finger and said segment being suitably connected so that when they are connected together through one of said contacts a signaling impulse is produced, a 115 spring motor for driving said contact finger over said contacts, a stop for preventing the movement of said contact finger by said spring motor, and means responsive to an incoming calling current to the associated telephone for controlling said stop to allow the spring motor to move said contact finger over said contacts and necessarily to stop after having made one complete rotation until another incoming calling current separate from the first shall be supplied subsequent to the completion of such rotation.

17. An automatic telephone signaling apparatus for producing a code signal, comprising a device for automatically making 130

- and breaking a circuit, and means controlled by an incoming calling current to the associated telephone for starting the operation of said circuit making and breaking means 5 and for positively stopping such operation after a cycle of operation regardless of the length of time the incoming calling current continues.
18. An automatic telephone signaling apparatus for producing a code signal, comprising two relatively movable members which move relatively to each other in a complete cycle having two parts and during one part only of such relative movement 15 produce an automatic making and breaking of a circuit, and means controlled by an incoming calling current to the associated telephone for causing one part of such relative movement and by the cessation of said incoming calling current for causing the other part of such relative movement.

19. An automatic telephone signaling apparatus for producing a code signal, comprising two relatively movable members 25 which move relatively to each other in a complete cycle having two parts and during such relative movement produce an automatic making and breaking of a circuit, and means controlled by an incoming calling current to the associated telephone for causing one part of such relative movement and by the cessation of said incoming calling current for causing the other part of such relative movement.

20. An automatic telephone signaling apparatus for producing a code signal, comprising means controlled by an incoming calling current to the associated telephone, and a device controlled by said means to automatically make and break a circuit which is supplied from a distant source and includes wires over which the said calling current is supplied.

21. In combination, a telephone, a circuit 45 leading from a distance to said telephone, means controlled by an incoming calling current to said telephone over said circuit, and a device controlled by said means for automatically starting and stopping the flow of 50 current over said circuit from a distant source.

22. In combination, a contact finger, a series of contacts, said contact finger and said series of contacts being movable relatively to each other in a plane so that the contact finger passes over said contacts in a definite path and engages them successively in passing, some of said contacts projecting sidewise from said plane in one direction 55 only and some in the other direction only, and a pair of connecting devices movable into engagement with varying numbers of the contacts which project on the two sides of said plane respectively.

23. In combination, a disk of insulating

material having a circumferential groove, a contact finger movable relatively to said disk and traveling in said groove, a series of contact fingers projected into said groove from one side of said disk, a second series of contact fingers projecting into said groove from one side of said disk, a second series of contact fingers projecting into said groove from the other side of said disk, two contact segments located on the two sides of the disks and movable into engagement with varying numbers of the two sets of contact fingers respectively, and an electro-magnet controlling the relative movement between said contact finger and said disk to permit a partial rotation between the two when the magnet is energized and the remainder of the rotation between the two when the magnet is de-energized, said finger engaging the contacts of said two sets only during one of said parts of said relative rotation.

24. In combination, a disk of insulating material having a circumferential groove, a contact finger movable relatively to said disk and traveling in said groove, a series of contact fingers projected into said groove from one side of said disk, a second series of contact fingers projecting into said groove from the other side of said disk, and two contact segments located on the two sides of the disks and movable into engagement with varying numbers of the two sets of contact fingers respectively.

25. In combination, a disk of insulating material having a circumferential groove, a contact finger movable relatively to said disk and traveling in said groove, a series of contact fingers projected into said groove from one side of said disk, a second series of contact fingers projecting into said groove from the other side of said disk, two contact segments located on the two sides of the disks and movable into engagement with varying numbers of the two sets of contact fingers respectively, and an electro-magnet controlling the relative movement between said contact finger and said disk to permit a partial rotation between the two when the magnet is energized and the remainder of the rotation between the two when the magnet is de-energized.

26. In combination, a subscriber's telephone of a common battery telephone system, and a signaling apparatus associated with said subscriber's telephone for producing a code signal, said signaling apparatus comprising a series of contacts, a contact finger movable relatively to said contacts to engage them in succession, and means controlled by the cessation of an incoming calling current to said subscriber's telephone to cause relative movement between said finger and said contacts to produce a making and breaking of the circuit for the common battery current supplied to said telephone.

27. In combination, a subscriber's telephone of a common battery telephone system, and a signaling apparatus associated with said subscriber's telephone for producing a code signal, said signaling apparatus comprising a series of contacts, a contact finger, means for moving said contact finger and said series of contacts relatively to each other so that the finger engages said contacts in succession, an electro-magnet connected to be energized by an incoming calling current to said telephone, and means controlled by said magnet for causing an initial preparatory movement between said series of contacts and said finger by said moving means upon the starting of said incoming calling current and for causing a current making and breaking movement between said series of contacts and said contact finger upon the cessation of said calling current to produce the desired code signal by a series of makes and breaks of the circuit for the common battery current supplied to said telephone.
- 25 28. In combination, a subscriber's telephone of a common battery telephone system, and a signaling apparatus associated with said subscriber's telephone for producing a code signal, said signaling apparatus comprising a series of contacts, a contact finger, means for moving said contact finger and said series of contacts relatively to each other so that the finger engages said contacts in succession, an electro-magnet connected to be energized by an incoming calling current to said telephone, and means controlled by said magnet for causing a current making and breaking movement between said series of contacts and said contact finger upon the cessation of said calling current to produce the desired code signal by a series of makes and breaks of the circuit for the common battery current supplied to said telephone.

30. In combination, a subscriber's telephone of a common battery telephone system, and a signaling apparatus associated with said subscriber's telephone for producing a code signal, said signaling apparatus comprising a series of contacts, a contact finger, said contact finger and said series of contacts being relatively movable so that the contact finger may engage the series of contacts in succession, an electro-magnet connected to be energized by an incoming calling current to said telephone, and means controlled by said magnet for causing a current making and breaking movement between said series of contacts and said contact finger upon the cessation of said calling current to produce the desired code signal by a series of makes and breaks of the circuit for the common battery current supplied to said telephone.
31. In combination, a subscriber's telephone of a common battery telephone system, and a signaling apparatus associated with said subscriber's telephone for producing a code signal, said signaling apparatus comprising a circuit making and breaking device connected to the circuit for the common battery current supplied to said telephone, and electro-magnetic means controlled by an incoming calling current to said telephone to cause said circuit making and breaking device to operate to produce a predetermined series of makes and breaks of the common battery current upon the cessation of said incoming calling current.
32. An automatic telephone signaling apparatus for producing a code signal, comprising a device for automatically making and breaking the circuit, and means controlling said device and controlled by an incoming calling current to the associated telephone and having different positions which it respectively assumes when said calling current does and does not flow and from a plurality of which it must be moved in order to produce a complete cycle of operation of said device.
33. An automatic telephone signaling apparatus for producing a code signal, comprising two relatively movable members which move relatively to each other in a complete cycle, and means controlling such relative movement and controlled by an incoming calling current and having different positions which it respectively assumes when such current does and does not flow and from a plurality of which it must be moved to produce a complete cycle of relative movement between such two members.
34. An automatic telephone signaling apparatus for producing a code signal, comprising a series of contacts, a contact finger movable over said contacts in cyclic suc-

sion, means for varying the effective arrangement of said contacts, and electrically operated means controlling the movement of said contact finger over said contacts and 5 having two positions which it respectively assumes when an incoming calling current does and does not flow, and away from both of which positions it must be moved in succession in order to produce a complete cycle of movement.

35. An automatic telephone signaling apparatus for producing a code signal, comprising a series of contacts, a contact finger movable over said contacts in cyclic succession, and electrically operated means controlling the movement of said contact finger over said contacts and having two positions which it respectively assumes when an incoming calling current does and does not flow, and away from both of which positions it must be moved in succession in order to produce a complete cycle of movement.

36. An automatic telephone signaling apparatus for producing a code signal, comprising a series of contacts, a contact finger movable over said contacts in cyclic succession, an electro-magnet which is energized by an incoming calling current to the associated telephone, and means operated by 25 said magnet for controlling the movement of said contact finger over said contacts, said means having two positions which it takes 30

respectively when said magnet is and is not energized and requiring to be moved from one of the positions to the other and then 35 back to the first in order to produce a complete cycle of movement of the contact finger over the contacts.

37. An automatic telephone signaling apparatus for producing a code signal, comprising a series of contacts, a contact finger movable over said contacts in cyclic succession, a spring motor for producing said movement, an electro-magnet energized by an incoming calling current to the associated 40 telephone, and stopping means operated by said magnet for controlling the movement of said contact finger over said contacts by said spring motor, said stopping means having two positions which it takes respectively 45 when said magnet is and is not energized and requiring to be moved from one of the positions to the other and then back to the first in order to produce a complete cycle of movement of the contact finger over the 50 contacts.

In witness whereof, I have hereunto set my hand and seal at San Francisco, California, this twentieth day of November, A. D. one thousand nine hundred and twelve.

DUDLEY D. WRIGHT. [L. s.]
Witnesses:

O. M. NICHOLS,
KATHERINE REARDON.
